UNITED STATES PATENT OFFICE.

LOUIS D. KEISWETTER AND WILLIAM S. ROBERTS, OF DENTON, KANSAS.

CRANK AND LEVER.

1,145,865.

Specification of Letters Patent.

Patented July 6, 1915.

Application filed February 19, 1913. Serial No. 749,463.

To all whom it may concern:

Be it known that we, LOUIS D. KEISWETTER and WILLIAM S. ROBERTS, citizens of the United States, residing at Denton, in 5 the county of Doniphan and State of Kansas, have invented certain new and useful Improvements in Cranks and Levers, of which the following is a specification, reference being had to the accompanying drawings.

This invention comprehends certain new and useful improvements in cranks and levers and has for a primary object to provide novel and improved means for converting rotary movement into reciprocatory movement.

Another object is to provide mechanism of this character which will be of extremely simple construction and highly efficient and 20 effective in use.

With the above and other objects in view, this invention consists in the novel features of construction, combination and arrangement of parts as will be hereinafter more 25 particularly set forth in the specification, pointed out in the claim and illustrated in the accompanying drawings, which form a part of this application and in which,

Figure 1, is a side elevational view of an 30 embodiment of our invention applied to a pump of ordinary construction. Fig. 2, is a front elevational view of the arrangement shown in Fig. 1. Fig. 3, is a top plan view of the upper portion of the invention as 35 herein disclosed.

Referring more specifically to the drawings, in which similar reference characters designate corresponding parts throughout the several views, 1 indicates the base which 40 is formed in sections positioned upon opposite sides of a pump 2 and above the platform 3, each section having a semi-circular recess 4 formed in one side to accommodate the pump 2 and the sections 1 being clamped 45 together by the clamp bolts 5 or other suitable means.

One of the sections 1 is considerably longer than the other section and projects beyond the platform 3, the purpose of which 50 will presently appear. This section 1 is braced by means of the bracing bars 6 which have their opposite ends bent, as shown at 7, one of the bent ends of each bar 6 being secured upon the platform 3 while the other

is secured to the long member 1 near its projected end. 55

Suitable bearing members 9 are provided upon the opposite ends of the upper face of the long member 1 to receive the crank shaft 8 and support the same above said 60 long member 1, the ends of the shaft projecting beyond the base member 1 and one projecting end of the shaft being bent to form the crank portion 10 while the drive wheel 11 is secured upon the opposite end of the 65 shaft. The shaft 8 is also provided with a central crank portion 12, the purpose of which will presently appear.

Secured to each of the crank portions 10 and 12 of the shaft 8 are the lower ends of 70 the pitman rods 14. The upper ends of the pitman rods 14 are connected by the arcuate connecting member 15 which has a vertical central opening to receive the reciprocating member 18 of the pump. The opposite ends 75 of the arcuate member 15 are connected with the upper ends of the pitman rods 14 by bolts 16 or other suitable means. The central upwardly extending collar 13 is provided upon the arcuate member 15 around 80 the central opening of the latter and the transversely extending pin 17 is positioned through this collar and through the reciprocating member 18 of the pump. Thus it 85 will be seen that as the drive wheel 11 is rotated by suitable power, to rotate the shaft 8, the pitman rods 14 are operated to move the arcuate member 15 and thus raise and lower the pin 17 to reciprocate the reciprocating member 18 of the pump 2. 90

While we have shown the preferred embodiment of our invention, it will be understood that we do not wish to be limited to this exact form, as minor changes in the details of construction may be made within the scope of 95 the appended claim without departing from the spirit of our invention.

Having thus described our invention, what we claim is:—

A device of the class described comprising 100 the combination with a pump including a reciprocating pump rod, of a cross head having a central opening to accommodate the reciprocating pump rod while the opposite ends of said cross head are directed 105 downwardly, said cross head being also provided with a lateral sleeve around the central opening and adapted for engagement

around the reciprocating pump rod and disposed in a direction away from the pump, a pivot member extended through said sleeve and reciprocating pump rod, pitman rods rigidly connected with the extremities of the cross head, and a crank shaft provided with operating means, said pitman rods being operatively engaged with the crank shaft.

In testimony whereof we hereunto affix 10 our signatures in the presence of two witnesses.

LOUIS D. KEISWETTER.
WILLIAM S. ROBERTS.
